UNITED STATES PATENT OFFICE.

CARLS ROSS, OF NEW YORK, N. Y.

FOLDING CRIB.

No. 914,309.

Specification of Letters Patent.

Patented March 2, 1909.

Application filed April 11, 1908. Serial No. 426,591.

To all whom it may concern:

Be it known that I, CARLS ROSS, a citizen of the United States, residing at New York, in the county of New York and State of New York, have invented new and useful Improvements in Folding Cribs, of which the following is a specification.

This invention relates to cribs and more particularly to folding or collapsible cribs which when not in use are by means of certain hinged parts collapsed so as to occupy a minimum amount of space, the particular feature of the invention being the collapsible head and foot pieces which are more fully described in the following specification, set forth in the claims and illustrated in the accompanying drawings, where:

Figure 1 is a perspective view of the improved crib. Fig. 2 is a cross sectional view 20 showing the crib partly folded.

The crib is supported at each end by the crossed legs 5 which are pivoted at a central point 6 and at their upper ends have attached to them a leaf of the hinges 7, the 25 other leaf being secured to the side pieces 8 made up of horizontal bars 9, vertical rods 10 and cord posts 11.

The bottom of the bed comprises two 30 hinged sections 12 which fold upward and are composed of the end pieces 13 and the connecting bars 14. The end pieces are connected by the middle hinges 15 and their ends are connected with the lower side bars 9 by means of the hinges 16. This allows 35 the crib to be folded as partly shown in Fig. 2 but it may be more completely collapsed by bringing the legs more closely together.

The head and foot pieces 17 and 18 are 40 made of flexible material such as canvas or rubber cloth and are carried by rollers 19 and 20, the latter being spring rollers of the ordinary curtain type which roll the fabric upon themselves when the sides of the crib are be-

ing folded together. As will be seen in Fig. 2 the side pieces are adapted to move toward 45 each other in parallel positions so that the flexible ends are easily wound about the rollers.

As long as a child is lying in the crib there is no danger of its collapse because of the 50 weight on the bottom 12 depressing the end pieces 13 and forcing the side pieces and legs outward and it is only when the crib is empty that it may be closed.

The spring rollers require no retaining 55 pawl when the pieces 17 are extended but are free to unroll or roll the end pieces as the crib is unfolded or folded.

A collapsible crib constructed in accordance with this invention is simple, cheap and 60 substantial, and it is obvious that alterations may be made in the details of the crib without departing from the essential features above described.

What I claim as new and desire to secure 65 by Letters Patent is:

1. In a folding crib, the combination with crossed legs connected by pivots, of side pieces hinged at top of same, a bottom hinged to the side pieces and divided in the middle 70 so as to fold and flexible end pieces carried by rollers and adapted to automatically wind on same when the crib is folded.

2. In a folding crib, the combination with crossed legs adapted to fold, of side pieces 75 hinged to same, a folding bottom hinged to the side pieces, automatic spring rollers on the side pieces, and end pieces of flexible material adapted to wind on the rollers when the 80 crib is folded.

In testimony whereof I affix my signature in presence of two witnesses.

CARLS ROSS.
